INGOT BUGGY DRIVE

Gordon Fox, Chicago, Ill., assignor to Koppers Company, Inc., a corporation of Delaware

Filed Jan. 5, 1954, Ser. No. 402,391

2 Claims. (Cl. 104—178)

The present invention relates to a transfer car drive system and more particularly to a drive system for an ingot buggy which transfers heated ingots from a row of spaced soaking pits to a metal working mill such as a blooming slabbing mill.

As is well known in the metallurgical arts, a blooming mill or slabbing mill is preceded by heating facilities termed soaking pits. A number of these pits are spaced in a row at regular intervals along the length of the soaking pit building. An ingot buggy or car runs along a track extending along one side of the row of these pits. Heated ingots, removed from the pits, are placed on the ingot buggy by an overhead crane and are transported from the respective pits to the mill.

In the prior art, various types of drives have been used for these ingot buggies. For example, electric motors have been mounted on the buggy, transmitting tractive effort to some portion of the buggy wheels. However, this general type of drive has not been entirely satisfactory because of the inherent difficulties involved in the operation and maintenance of required conductor rails and because of the limitations of tractive drive on only a portion of the buggy wheels. Moreover, it has been found undesirable to have the motor mounted on the buggy in close proximity to the handling of the hot ingot.

In order to eliminate some of these difficulties, more recent ingot buggies have been driven by tow cables. The cables, attached to the head and tail end of the buggy have been driven from the same capstan or winch mechanism in response to the same motor drive. This has necessitated the provision of a tunnel or its equivalent, generally under the ingot buggy track. The tail cable passes to the tail end of the track, assuming the operating winch to be located at the head end of the track. A take-up means has also been necessary to keep the cables reasonably taut in the event of cable stretch. Although this cable scheme provides rapid acceleration and deceleration of the buggy without wheel slippage and further eliminates electrical conductors along the trackway, the provision of a tunnel under the ingot buggy track has proved to be undesirable.

The present invention provides a means for retaining the advantages of the aforementioned cable drive, but eliminates the need for a cable tunnel.

One of the features of the present invention is to provide a drive system for an ingot buggy whereby ingots may be delivered to the mill as fast as they can be processed, regardless of the length of the ingot buggy travel.

Another feature of the present invention is to provide a drive system for an ingot buggy which permits close control and rapid spotting of the buggy.

Another feature of the present invention is to provide a drive system that can be readily controlled by a single operator positioned a safe distance from the soaking pits.

Another feature of the present invention is to provide

a drive and control system which places minimum dependence, for its action, upon an operator.

Another feature of the present invention is to provide a drive system that permits the use of winches located remotely from the ingot buggy line of travel.

Another feature of the present invention is to provide a drive system that is efficient in its operation and economical in its maintenance.

Still another feature of the present invention is to provide a drive system which avoids acceleration of an ingot buggy to high speeds when the buggy is near the limits of travel.

Numerous other features of the combined ingot buggy and drive system will become apparent from the description which follows.

More particularly, the present invention provides a transfer car drive system comprising a pair of spaced winches; a transfer car positioned between the winches; a first cable having one end attached to one of the winches and its opposite end attached to the transfer car so as to pull on the transfer car in one direction; a second cable having one end attached to the other of the winches and its opposite end attached to the transfer car so as to pull on the transfer car in an opposite direction from the first cable pull; a winch drive mechanism for each of the winches; a pair of motors, each motor being adapted to drive one of the winches, through the winch drive mechanism; a generator system adapted to supply electric power to the motors, and control means for the generator system adapted to selectively govern the polarity and the relative voltages supplied by the generator system to the armatures of the respective motors, thereby causing differences in pull on the cables connected to the winches and thus effecting movement of the transfer car to which the cables are attached.

It will be obvious to one skilled in the art that various changes can be made in the arrangement, form, construction and type of the elements disclosed without departing from the scope or spirit of this invention.

Reference will now be made to the accompanying drawings which illustrate and exemplify an elementary embodiment of the apparatus of the invention in a preferred type of construction.

Figure 1 represents a schematic drawing of the arrangement and drive system of an ingot buggy which connects the soaking pits with the blooming or slabbing mill.

Figure 2 represents an electrical diagram for the ingot buggy drive system. For convenience, this figure is divided into three parts, indicated as Figure 2, part A; Figure 2, part B; and Figure 2, part C.

Referring to Figure 1 of the drawings; an ingot buggy track 10 is disclosed as positioned along one side of a row of spaced soaking pits, 1 to 6. The track 10 connects the soaking pits with a mill 11. Positioned on the track 10 is an ingot buggy 12. Connected to the tail end of the buggy is one end of a cable 14. The other end of this cable is connected to a winch 20. Connected to the head end of the buggy is one end of a cable 16, the other end of this passes over snatch block 17 or deflector sheave and is connected to a winch 18. The deflector sheave permits the winch to be remotely located while still preserving cable pulls in opposition, substantially in line with the tracks. It is to be understood that such sheaves can be used with both winches if so desired. The winch 20 is driven by a motor 2M through winch drive gearing arrangement 24. The winch 18 is driven by a motor 1M through winch drive gearing arrangement 22.

The winch 18 is further provided with two limit switch cam mechanisms through a gearing arrangement 30. It is to be understood that in another embodiment of this invention the limit switch cam mechanisms can be mounted on the winch 20 instead. One of these limit

switch cam mechanisms is designated VLS and represents a vernier limit switch cam mechanism. The other limit switch is designated SLS and represents a selective limit switch cam mechanism. It is to be further understood that limit switch mechanisms other than of the cam type can also be used with the present invention.

When the heated ingots are taken from the first pit, nearest the mill, the ingot buggy movement is short. When the heated ingots are taken from remote pits, the ingot buggy movement is greater. In order to keep pace with the mill, ingots must be delivered as rapidly as the mill can process them, regardless of the length of the ingot buggy travel. To have adequate capacity when serving remote pits, the speed of the buggy must be high (such as 800 feet per minute), while when serving close pits, the speed can be low (such as 400 feet per minute). The selective movement and speed of the ingot buggy 12 along the track 10 is obtained through these two aforementioned limit switch, VLS and SLS cam mechanisms.

The selective limit switch cam mechanism (SLS) rotates approximately 320° for the total cable travel. Thus, this cam mechanism serves only as a coarse means for controlling movement of the ingot buggy from pit to pit, and pit to mill. Therefore, the vernier limit switch cam mechanism (VLS) is provided. This vernier limit switch cam rotates 360° when the ingot buggy travels the distance between center lines of adjacent pits, permitting accurate movement of the buggy, the contacts effecting slow-down, and the stopping operations. Broadly, the cam mechanism SLS merely designates which of the pits the car is to stop before. This designation need be only rough, since the vernier limit switch VLS governs accurate slow-down and stop functions.

It is to be noted, that since the distance from the first pit to the mill is usually not the same as the distance from pit to pit, separate cams on the vernier limit switch are necessary to provide for automatic slow-down and stopping of the car at the mill. This vernier action is effective only when the car is at or near its terminal position at the mill and is of no effect at regularly spaced intervals along the track relating to the mill terminal position, corresponding to complete rotations of the vernier limit switch. It is further to be noted that the vernier cams can be arranged and adjusted in accordance with the distance from pit to pit and in accordance with the distance from pit number 1 to the mill.

In operation, movement of the ingot buggy is controlled by an operator positioned in a pulpit adjacent to the point of delivery of the ingots from the buggy to the receiving table in advance of the mill. Since this position is located a considerable distance from the pits, accurate spotting of the car is made possible by an electrical control system for the motors 1M and 2M including a selector switch shown as SS1, SS2, SS3, SS4, SS5, SS6, in Fig. 2, part C, a mill push button, designated Mill, a Stop button, a pit push button, designated Pit, a plurality of relays and their contacts and the contacts of the vernier limit switch cam mechanism and selector limit switch cam mechanism. In general, the selector switch, SS, can be set for movement of the ingot buggy to any one of the pits 1, 2, 3, 4, 5, or 6. The Mill push button can be set for movement of the ingot buggy to the mill and the Pit push button can be set for movement of the ingot buggy to or between pits, in both directions.

In a typical operation, the selector switch SS is set for the pit to which the ingot buggy is to be moved, then the Pit button is depressed. The buggy moves to a position opposite the selected pit, slows down and stops. If the buggy movement is made at fast speed, the slow-down must and will be initiated further in advance of the stopping position than if the movement takes place at intermediate speed. This is effected by the different cams on the aforescribed vernier limit switch cam

mechanism, VLS. Movements at fast speed are restricted, in the instance described, to trips from the mill to remote pits 4, 5 or 6 and to trips from pits 4, 5 and 6 to the mill. Movements between the mill and pits 1, 2 and 3 are made at intermediate speed. Movements from one pit to another, which occur only occasionally, are made at intermediate speed. For a given movement, one winch with its motor pulls the car along the track and the other winch with its motor holds back against the car movement, keeping both cables fairly taut. The relative rope pulls of the respective "driving" and "dragging" motors is controlled to cause acceleration or deceleration. This control is done by controlling the applied voltages, counter-voltages, and armature currents of the respective driving motors through the aforementioned control system which is described in detail below. This control system is represented in Figure 2 of the drawings and, for the purposes of clarity, a statement of the significance of the numerals and letterings used therein is 20 given as follows:

The letters ACC (line 62) refer to an accelerating relay coil. This relay works on the field of generator 2G to affect current flow in a local circuit including the armatures of motors 1M and 2M. The current flow in this 25 local circuit emphasizes the "motor" effect of the boosted motor and correspondingly contributes to a "drag" effect of the other motor.

The letters DEC (line 63) refer to a decelerating relay coil which acts like relay coil ACC to effect a local circuiting current but of reduced value as compared with that set up by relay coil ACC. In combination with the falling off of the voltage of generator 1G, it causes deceleration.

The letters 1F and 2F (line 59) refer to forward directional relay coils. The principal function of these relay coils is to orient the polarity of generator 1G, in order to govern the direction of movement.

The letters 1R and 2R (line 61) refer to reverse directional relay coils, functioning inversely to 1F and 2F.

The letters FS (line 65) refer to a fast speed relay coil. The principal function of this relay coil is to maximize the strength of the reference field of generator exciter GE, thereby causing generator 1G to develop a relatively high voltage, resulting in high speed operation of 45 motors 1M and 2M.

The letters FX (line 58) refer to an auxiliary relay coil which functions as a directional relay coil for the field of generator 2G.

The letters RX (line 60) refer to an auxiliary relay 50 coil functioning inversely of FX.

The letters 1M1 and 2M1 (lines 41-43) refer to contacts which rearrange the armature circuits of motors 1M and 2M, connecting one or the other directly across the generator 1G.

The letters 1T1 and 2T1 (lines 41-43) refer to contacts which selectively introduce generator 2G into boosting relationship with respect to motors 1M or 2M.

The letters BR1 and BR2 (line 56) refer to coils which are connected with brakes for the winch drives. When 60 these coils are energized, the brakes which are holding the winch drives are released.

The letters MR (line 66) refer to a mill (reverse) relay coil. This coil sets up circuits which cause movement of the ingot buggy toward the mill to be continued 65 until the mill is reached.

The letters MRF (line 66) refer to a mill fast relay coil. This relay coil acts to insure that certain movements of the ingot buggy toward the mill (namely, from pits 4, 5 and 6) will be at fast speed.

The letters MRI (line 66) refer to a mill intermediate speed relay coil. This coil acts to insure that certain movements of the ingot buggy toward the mill, (namely from pits number 1, 2 and 3) will be at intermediate speed.

The letters IS (line 64) refer to an intermediate speed

relay coil. This coil functions to moderate the strength of the GE Reference Field, thereby causing generator 1G to develop an intermediate voltage, resulting in intermediate speed of movement of the ingot buggy.

The letters PFD (line 68) refer to a pit (forward) relay coil. This coil sets up a circuit which leads to movement in a forward direction (away from the mill).

The letters PRV (line 69) represent a pit reverse relay coil. This coil sets up a circuit which leads to movements between pits (toward the mill).

The letters PFF (line 67) refer to a pit forward fast relay coil. This coil acts to insure fast movement from the mill to pits numbers 4, 5 and 6.

The letters PFX (line 70) refer to a pit forward auxiliary relay coil. This coil acts to cause the coil PFF to energize on trips starting from the mill to pits numbers 4, 5 and 6. It also acts to cause relay coil PFI to energize for trips from one pit to another in the forward direction (from the mill).

The letters PRI (line 67) refer to a pit reverse intermediate relay coil. This coil causes movements between pits toward the mill to take place at intermediate speed.

The letters UV refer to an undervoltage relay coil.

For the purposes of uniformity in the electrical diagram of Fig. 2, contacts biased to open position are indicated by vertical parallel lines, and contacts biased to closed position are indicated by vertical parallel lines with a diagonal line therethrough.

In general, the contacts are identified by the characters applied to their operating relay coils, the contacts being differentiated by the addition of suffixes. For example, relay coil 1F (line 59) controls the contacts 1F1, 1F2 and 1F3 (line 51).

Referring to Figure 2 of the drawings, line 44 contains generator 1G which applies to basic power to drive the two winch drive motors, 1M and 2M.

Line 41 which extends across the main generator 1G includes the contact 1M1 (normally biased to open) and the motor 1M in series therewith. In parallel with the contact 1M1 is the booster generator 2G and the contact 2T1 (normally biased to open) in series with this booster generator.

Line 43 which also extends across the main generator 1G includes the contact 2M1 (normally biased to open) and the motor 2M in series therewith. The booster generator 2G and the contact 1T1 (normally biased to open) in series therewith is in parallel with the contact 2M1.

Line 45, including the GE Field Voltage Control, extends across the generator 1G.

Line 46 includes the field of generator 1G.

Line 47 extending across this field includes the exciter designated GE.

Line 51 extends from the positive side of a 250 volt D.C. line, designated POS (other voltages can be used) through the contact RX1 (normally biased to open), the contact FS4 (normally biased to open), the resistance unit A, the contact 1F2 (normally biased to open), the contact 1R2 (normally biased to open) to the negative side of the line, designated NEG. In parallel with the contact RX1, is the contact FX1 (normally biased to open). In parallel with the contact FS4 and resistance unit A is the contact IS4 (normally biased to open) and the resistance unit B in series therewith. Contact IS4 and resistance unit B are also in series with contact FX1. Also in parallel with the contact FS4 and resistance unit A is the contact FS5 (normally biased to closed), the contact IS5 in series therewith (normally biased to closed) and the resistance unit C in series therewith. In parallel with the contact 1F2 and the contact 1R2 in series therewith, are the contacts 1R3 (normally biased to open) and 1F3 (normally biased to open) in series therewith. These latter two contacts are also in series with resistance unit C. Connected to the line which connects the contacts 1F2 and 1R2 is one side of the generator exciter GE (line 47), through the contact 1F1 (normally biased to

closed). Connected to the line which connects contacts 1R3 and 1F3 is the other side of the generator exciter GE (line 47) through the contact 1R1 (normally biased to closed). One end of the GE Reference Field is connected to the line which connects contacts 1F2 and 1R2. The other end of the line of the GE Reference Field is connected to the line connecting the contacts 1R3 and 1F3.

Line 52 extends from POS through contact RX2 (normally biased to open), through contact FX2 (normally biased to open) to NEG.

Line 53 extends from POS through contact FX3 (normally biased to open), contact RX3 (normally biased to open) to NEG.

Extending across lines 52 and 53 is a line which includes

15 the variable resistance unit E, the variable resistance unit D, and the field of generator 2G, all in series. One end of this line is connected intermediate the contacts RX2 and FX2 (line 52), and the other end of this is connected intermediate the contacts FX3 and RX3 (line 53). In series with the adjustment arm of resistance unit D and parallel with resistance unit E is the contact ACC1 (normally biased to open). In series with the adjustment arm of the resistance unit E is the contact DEC1 (normally biased to open).

20 Line 54 extends from POS through 1M field to NEG.

Line 55 extends from POS through 2M field to NEG.

Line 56 extends from POS through contact MR6 (normally biased to open), relay coil BR1 and relay coil BR2 to NEG. In parallel with contact MR6 are contacts 25 PFD5 (normally biased to open) and contact PRV6 (normally biased to open).

Positioned between lines 56 and 57 in both POS and NEG line are the fuses F which protect the remainder of the control equipment thereafter.

30 Line 57 extends from POS through the contact (normally biased to open) of the Reset button, through the Protective Devices in series therewith (not shown), and the undervoltage relay coil UV to NEG. In parallel with the reset button is contact UV1 (normally biased to open).

35 Contact UV1 in series with contact UV2 (normally biased to open) connects the line designated POS to the line designated POS'.

Line 58 extends from POS' through contact PFD1 (normally biased to open), contact 2M2 (normally biased to closed) in series therewith, and relay coil 1M in series therewith to NEG. In parallel with relay coil 1M are the relay coils FX and 1T.

40 Line 59 extends from POS' through contact PFF1 (normally biased to open), the contact 1M2 (normally biased to open) in series therewith, contact 2R1 (normally biased to closed) in series therewith, and relay coil 1F in series therewith to NEG. In parallel with the contact PFF1 is the contact PFI1 (normally biased to open). In parallel with relay coil 1F, is relay coil 2F.

45 Extending across lines 58 and 59, is a line which contains the contact VLS1. One end of this line is connected to the line connecting contacts PFD1 and 2M2, and the other end of this line is connected to the line connecting the contacts PFF1 and 1M2.

50 Line 60 extends from POS' through contact PRV1 (normally biased to open), the contact 1M3 (normally biased to closed) and the relay coil RX to NEG. In parallel with the relay coil RX are the relay coils 2M and 2T. In parallel with the contact PRV1 is the contact MR1 (normally biased to open).

55 Line 61 extends from POS' through the contact MRI1 (normally biased to open), through the contact 2M3 (normally biased to open) in series therewith, through the contact 2F1 (normally biased to closed), through the relay coil 2R in series therewith, to NEG. In parallel with relay coil 2R is the relay coil 1R. In parallel with the contact MRI1 are the contacts MRF1 (normally biased to open) and PRI1 (normally biased to open). Extending across the line 60 and 61 is a line which contains the contacts PRV2 (normally biased to open) and VLS2 in

series therewith. One end of this line is connected to the line which connects contacts PRV1 and 1M3, the other end of this line is connected to the line which connects contacts MRI1 and 2M3. These contacts PRV2 and VLS2 which appear in the line extending across the lines 60 and 61 are so arranged as to be in series with the contact MRI1 which has been aforescribed to be in parallel with contact PRV1 of line 60. Further, in parallel with the contacts PRV2 and VLS2 are the series connected contacts MR2 (normally biased to open) and VLS3.

Line 62 extends from POS' through contact IS2 (normally biased to open) and the relay coil ACC in series therewith to NEG. In parallel with the contact IS2 is the contact FS2 (normally biased to open).

Line 63 extends from POS' through the contact IS3 (normally biased to closed), contact FS3 (normally biased to closed) in series therewith, and the relay coil DEC in series therewith to NEG.

Line 64 extends from POS' through the contact PRI2 (normally biased to open), the contact FS6 (normally biased to closed) in series therewith, and the relay coil IS in series therewith to NEG. In parallel with the contact PRI2 and with each other are the contacts PRI2 (normally biased to open) and MRI2 (normally biased to open). Paralleling this arrangement is the contact PRV3 (normally biased to open) in series with the contact VLS4, and paralleling this arrangement is the contact PFD2 (normally biased to open) in series with the contact VLS5. Paralleling the line which includes the contacts PFD2 and VLS5 is a line which includes the contact MR3 (normally biased to open) in series with the contact VLS6.

Line 65 extends from POS' through contact MRF2 (normally biased to open), contact PFI3 (normally biased to closed) in series therewith, contact MRI3 (normally biased to closed) in series therewith, and relay coil FS in series therewith to NEG. In parallel with contact MRF2 is the contact PFF2 (normally biased to open). In parallel with this arrangement is the contact MR3 (normally biased to open) in series with the contact VLS8. In parallel with the line including the contacts MR3 and VLS8 is a line including aforementioned contact PFD2 in series with contact VLS7.

Positioned in the positive line between lines 65 and 66, in series therewith, is stop-button designated Stop (normally biased to closed). This button connects line designated POS' with a line designated POS''.

Line 66 extends from POS'' through the Mill push button, through contact PFD3 (normally biased to closed) in series therewith, through the contact PRV4 (normally biased to closed) in series therewith, through the contact SLS10 in series therewith, through the contact MRF3 (normally biased to closed) in series therewith, and through the relay coil MRI in series therewith, to NEG.

In parallel with the Mill push button of line 66 are the contacts MRI4 (normally biased to open) and MRF6 (normally biased to open).

In parallel with contacts SLS10, MRF3, and relay coil MRI in series, is another line containing contacts 2R2 (normally biased to open), MR4 (normally biased to open) in series therewith, and relay coil MR in series therewith. Paralleling contacts 2R2 and MR4 are contacts MRF5 (normally biased to open) and MRI5 (normally biased to open).

Paralleling the contact MRF3 and relay coil MRI is a line containing the contact SLS20 and the relay coil MRF. Paralleling the contact SLS20 is a contact MRF4 (normally biased to open).

Line 67 extends from POS'' through Pit button in series with contact MR5 (normally biased to closed), contacts SS1, SLS1, and relay coil PFI to NEG. Paralleling the pit button are the contacts PFI4 (normally biased to open), PRI3 (normally biased to open), and contact

PFF3 (normally biased to open). Paralleling the contacts SS1 and SLS1 is a line containing the series connected contacts SS2 and SLS2. A second line containing the series connected contacts SS3 and SLS3 also parallels the contacts SS1 and SLS1. Paralleling the contact SLS1 and relay coil PFI is a line containing the series connected contact SLS11 and the relay coil PRI. Paralleling the contact SLS2 and the relay coil is a line containing the contacts SLS22 in series with the relay coil PRI. Paralleling the contact SLS3 in series with the relay coil PFI is a line containing the contact SLS33 in series with the relay coil PRI. Positioned in parallel with the contacts SS1, SLS1, and the relay coil PFI is a line containing the contact SS4, in series with the contact SLS4, PFX2 (normally biased to open), and the relay coil PFF. The contact PFX2 is paralleled by a contact PFF5 (normally biased to open), in series with the contacts PFF4 (normally biased to closed), PFX1 (normally biased to closed) and the contact SLS3.

Paralleling the series connected contacts SLS4, PFX2 and the relay coil PFF is a line including the contact SLS44 and the relay coil PRI.

Positioned in parallel with the contacts SS4 and SLS4 is a line containing the contacts SS5 and SLS5.

Positioned in parallel to the contact SLS5 in series with the contact PFX2 and relay coil PFF is a line containing the series connected contact SLS55 and the relay coil PRI.

Also positioned in parallel with the series connected contacts SS4 and SLS4 is a line containing the series connected contacts SS6 and SLS6.

Positioned in parallel with the contacts SLS6, PFX2 and relay coil PFF is a line containing the series connected contact SLS66 and relay coil PRI.

Line 68 runs from POS'' through the contact PFF6 (normally biased to open), the relay coil PFD to NEG. Positioned in parallel with the contact PFF6 is the contact PFI5 (normally biased to open). Also positioned in parallel with the contact PFF6 is a line containing the series connected contacts 2F2 and PFD4 (normally biased to open).

Line 69 extends from POS'' through contact 2R3 (normally biased to open), through contact PRV5 (normally biased to open), through relay coil PRV to NEG. Positioned in parallel with the contacts 2R3 and PRV5 is the contact PRI4 (normally biased to open).

Line 70 runs from POS'' through the contact SLS30, the relay coil PFX to NEG.

It is to be noted that Figures 2B and 2C further disclose broadly the cam developments for the vernier limit switch and selector limit switch, respectively.

It is to be noted that the vernier limit switch rotates through 360° while the transfer car travels the distance from the center line of one pit to the center line of an adjacent pit. Limit switch VLS makes about seven (7) revolutions during a complete travel from the mill to the opposite extremity of travel. Limit switch VLS rotates in one direction while the transfer car moves forward (away from mill) and in the other direction when the transfer car moves in reverse (toward the mill).

VLS1—Signals stop at a soaking pit when traveling forward (away from mill).

VLS2—Signals stop at a soaking pit when traveling reverse (toward mill).

VLS3—Signals stop at the mill (from reverse travel).

VLS4—Signals slow-down preparatory to stop at a soaking pit when traveling reverse (always from intermediate speed).

VLS5—Signals slow-down preparatory to stop at a soaking pit when traveling forward at intermediate speed.

VLS6—Signals slow-down preparatory to stop at the mill when traveling reverse at intermediate speed.

VLS7—Signals slow-down preparatory to stop at a soaking pit when traveling forward at fast speed.

VLS8—Signals slow-down preparatory to stop at the mill when traveling at fast speed.

As can be seen from a study of the circuit disclosed in Figure 2 of the drawings, the motors 1M and 2M are supplied from two generators, namely, 1G and 2G. Generator 1G supplies adjustable voltage to the system as a whole. Generator 2G is a smaller generator which supplies as supplementary or booster voltage. The power for the drive as a whole comes mainly from the generator 1G. The generator 2G simply supplies differential voltage which causes a local flow of current through the motor armatures and the booster generator to cause one motor to tend to run faster than the other, thereby causing one to act as a "driving" unit and the other to act as a "dragging" unit.

The voltages of generator 1G and 2G are regulated by the amount of their respective field excitations. The voltage of generator 1G is reversed to determine the general direction of movement of the ingot buggy toward the mills or away from the mill. Similarly, the voltage of 2G is reversed so that its action is properly related to the voltage of 1G.

For example, when generator 1G has its voltage reversed it is necessary also to reverse the generator voltage of 2G. This is accomplished by reversing the fields which excite generator 1G and simultaneously reversing the flow of current through the fields which excite generator 2G. For one direction of movement it is desirable that the booster generator 2G be in circuit with one motor, for example, motor 1M. For the other direction of movement, it is desirable that the booster generator 2G be connected in circuit with motor 2M. The selection as to which motor gets the benefit of the booster voltage is made by means of contactors 1M1, 2T1, 1T1 and 2M1 as afore-described. Contactors 1M1 and 1T1 are closed for one direction of movement and contactors 2M1 and 2T1 are closed for the other direction of movement.

The field of generator 1G is excited through the exciter GE positioned in line 47. This exciter is in turn excited in part by a reference field supplied from a 250 volt constant potential circuit, designated in the drawing as POS-NEG, and in part by another field which is connected across generator 1G, responding to the voltage thereof. The control field responsive to generator 1G is in opposition to the reference field supplied from the 250 volt circuit. The speed of operation of the ingot buggy is determined primarily by the voltage developed by generator 1G. By controlling the amount of resistance connected in series with the reference field of exciter GE, the voltage of the generator 1G can be controlled.

In line 51 the several resistance units A, B and C are each provided with the contacts FS4, IS4, and the contacts FS5 and IS5 respectively. Dependent upon which of these contacts is open and which is closed, the resistance in circuit with the reference field is varied, and accordingly, the excitation of generator 1G is varied. The movement speed of the ingot buggy is in accord with this change of voltage.

It has been noted that the directions of the fields must be reversed in order to reverse the direction of movement of the ingot buggy. The fields of the exciter GE are reversed by means of contacts 1F2 and 1F3 for one direction of movement, and by means of contacts 1R2 and 1R3 for the other direction of movement. The corresponding reversal of the fields of the booster generator 2G are determined by the operation of contacts RX2 and RX3 for one direction of movement, and contacts FX2 and FX3 for the other direction of movement. The existence of the reference field is determined by the closure of either contacts RX1 or FX1 as the case may be. When both of these contacts are open the reference field is not connected across the 250 volt system. How-

ever, there might be a little residual magnetism in the poles of this exciter, causing it to set up some excitation in the field 1G and thereby causing 1G to generate at low voltage. This voltage is killed by short circuiting 5 of the reference field of GE across its own armature. The direction of flow of current in the reference field opposes the voltage of exciter GE, causing a suicide effect.

The amount of boosting effect of generator 2G is determined by its field strength. This in turn is influenced 10 by the amount of resistance in circuit with the field, and this in turn is determined by the open or closed position of contacts ACC1 or DEC1 (lines 52 and 53).

The brakes applied to the motors 1M and 2M, are 15 controlled by the relay coils BR1 and BR2, respectively, through any one of three contacts MR6, PFD5 and PRV6 (line 56). When movement is toward the mill and is destined to go all the way to the mill, the brakes are controlled through contact MR6. When the movement 20 is to be made in the direction of the mill from one pit to another pit, the brakes are controlled through contact PRV6. When the movement is in a direction away from the mill, the brakes are controlled through contact PFD5.

In order to describe the operation of the circuit for 25 Figure 2 more completely the sequence of operation in this circuit is described for five different movements of the ingot buggy as follows:

- (1) Movement of the ingot buggy from pit 4 to the mill.
- (2) Movement of the ingot buggy from pit 3 to the mill.
- (3) Movement of the ingot buggy from the mill to pit 4.
- (4) Movement of the ingot buggy from pit 4 to pit 2.
- (5) Movement of the ingot buggy from pit 1 to pit 5.

Sequence of trip from pit 4 to the mill

Assume the undervoltage relay coil UV in line 57 to be energized. Contacts UV1 and UV2 are thus closed. The Mill button in line 66 is pushed closed and the circuit is from POS' through PFD3, PRV4, SLS10, SLS20 and the relay coil MRF to NEG. Actuation of relay coil MRF causes contacts MRF6 and MRF4 to close, providing a holding circuit. Actuation of this coil MRF further completes the circuit through MRF5 and causes relay coil MR to be energized. The actuation of coil MR completes the circuit from POS' through the contacts MR1, 1M3, and relays RX, 2M and 2T to NEG (line 60).

It is to be noted further that the energization of coils MRF and 2M completes the circuit from POS', through contacts MRF1, 2M3, 2F1 and coils 1R and 2R (line 61). The actuation of coil 2R completes the holding circuit for coil MR through contacts 2R2 and MR4 (line 66). Actuation of coils 2M and 2T establishes the relation of generator 2G to boost the voltage applied to the motor 1M by closing the contacts 2M1 and 2T1. The actuation 55 of coil 1R causes the contacts 1R2 and 1R3 to establish a direction of the GE field, hence, the polarity of voltage 1G and direction of movement (toward the mill). The actuation of coil MR (above) energizes and releases brakes through the coils BR1 and BR2 (line 56). The actuation of coil RX (line 60), sets up the circuit (line 51) from POS through contacts RX1, FS4, 1R3, GE Reference Field and 1R2 to NEG, starting the voltage buildup in generator 1G. It further establishes the circuit (line 52) through contacts RX2, 2G field and RX3 determining the booster voltage polarity (lines 52 and 53). The energization of coil MRF (line 66) also energizes coil FS (line 65) through the contacts MRF2. This causes closure of contacts FS4. This also closes contacts FS2 (line 62) causing the relay coil ACC to be energized. Closure of contacts ACC1 (lines 52 and 53) boosts the voltage of generator 2G and increases the differential rope pull since motor 1M has more voltage impressed on it than motor number 2M, hence 1M acts 60 as a "motor" and 2M tends to act as a generator or

"drag." The voltage of generator 1G builds up, increasing speed of motors 1M and 2M, the GE control field is built up also. This field opposes the reference field and limits the voltage of generator 1G. Because of the small resistance in the circuit of FS4, the effect of the GE Reference Field is maximum and therefore maximum motor speed is obtained as a result of the maximum voltage developed by generator 1G. As the buggy travels toward the mill, the limit switch contact VLS3 (lines 60 and 61) is opened at spaced intervals, but no effect results because it is covered by the contact MRF1 (line 61).

When the buggy approaches close to the mill the limit contact SLS10 (line 66) opens, thereby deenergizing the coil MRF. This would result in the deenergization of the coil FS (line 65) because of the opening of contact MRF2, except for covering circuits, through MR3 and VLS8. When the VLS8 contact is opened in due course, coil FS is deenergized. The deenergization of coil FS opens contact FS4 (line 51) and closes contact FS5, causing voltage of generator 1G to decrease. The opening of contact FS2 (line 62) and closure of FS3 (line 63) deenergizes coil ACC and energizes coil DEC, decreasing differential pull of motor 1M in comparison with motor 2M, facilitating deceleration. The speed of the ingot buggy drops to a slow or "creeping" value.

Final stop is effected when limit contact VLS3 opens. This occurs since the cover circuit through MRF1 (line 61) is now open. This results in the deenergization of coils 1R and 2R, killing the voltage of the exciter GE. The deenergization of coil 2R further causes the contact 2R2 to be opened, and the coil MR to be deenergized, because contact MRF5 (line 66) is already open. The opening of contact MR6 (line 56) releases the brakes.

Sequence of trip from pit 3 to the mill

If the buggy has started toward the mill from pit 3 instead of pit 4, the limit contact SLS20 (line 66) would have been ineffective, hence the coil MRI would have been actuated instead of the coil MRF. The sequence of events would then be the same except contacts would be responsive to the coil MRI instead of responsive to the coil MRF. The coil FS (line 65) would not be energized because of open contact MRI3 and the coil IS (line 64) would be energized instead, contacts MRI2 and FS6 being closed. The closure of contact IS4 (line 51) would limit the voltage of generator 1G to a lower value, and a lesser running speed would result.

Sequence of trip from mill to pit 4

When the ingot buggy is in the mill position the coil PFX is energized through the contact SLS30 (line 70). The selector switch is then set by the operator to close the contact SS4 (line 67). Upon pushing the Pit button (line 67), the circuit through contacts MR5, SS4, SLS4, PFX2 and through the coil PFF is complete to NEG. Actuation of the coil PFF closes the contact PFF5 to form a holding circuit. The Pit button is shunted by the contact PFF3 which is closed by actuation of this coil.

The closure of contact PFF6 (line 68) completes the circuit through the coil PFD and energizes the same. This results in a closure of the contact PFD1 (line 58), leading to the energization of coils FX, 1M and 1T.

The closure of contact PFF1 (line 59) as a result of the energization of the coil PFF, completes the circuit through contacts 1M2, 2R1 and through the coils 1F and 2F, thereby actuating these coils. The energization of coil 2F completes the holding circuit for the coil PFD (line 68) by closing the contact 2F2. Energization of coils 1M and 1T (line 58) establishes the relationship of the generator 2G to boost the voltage applied to motor 2M.

The energization of coil 1F (line 59) establishes the direction of exciter GE Reference Field through the con-

tacts 1F2 and 1F3, hence the polarity of voltage 1G and the direction of movement away from the mill (forward).

The energization of coil PFD (line 68) as aforescribed causes the brakes to be released through coils BR1 and BR2 by closing the contact PFD5 (line 56). The energization of coil FX (line 58) sets up the circuit from POS (line 51) through the contacts FX1, 1F2, the GE Reference Field, 1F3, to NEG. The energization of this coil FX further establishes the circuit through the contacts FX2 and FX3, determining the booster voltage polarity. The energization of coil PFF (line 67) as earlier described causes the coil FS (line 65) to be energized through contact PFF2. This causes closure of FS4, completing the circuit for the GE Reference Field, causing voltage to build up in generator 1G. This also in turn causes the contact FS2 (line 62) to be closed thereby energizing the coil ACC.

Contact ACC1 (lines 52—53) is closed and the voltage of generator 2G is boosted, establishing a tendency for the motor 2M to act as a "motor" and the motor 1M to act as a generator or a "drag." The voltage build up of generator 1G is determined by the closure of contact FS4 and the opening of contact FS5 and is maximum. High running speed results. As the buggy travels away from the mill, limit switch contact VLS1 (lines 58—59) is opened at spaced intervals but there is no effect because contact PFF1 acting as a cover is closed.

When the buggy approaches pit 4, limit contact SLS4 (line 67) opens, thereby deenergizing the coil PFF. This would result in a deenergization of the coil FS (line 65) because of the opening of contact PFF2 but this does not take place due to the cover circuit through the closed contacts PFD2 and VLS7. When the contact VLS7 is opened in due course, the coil FS is then deenergized.

The deenergization of coil FS opens the contact FS4 (line 51) and closes contact FS5, causing the voltage of generator 1G to decrease. Opening contact FS2 (line 62) deenergizes the coil ACC, closure of contact FS3 (line 63) causes the coil DEC to be energized, affecting the differential pulls of motors 1M and 2M, encouraging deceleration. The speed of the buggy drops to a low value.

The final stop is effected when the limit contact VLS1 opens, the cover circuit through PFF1 (line 59) being now open. This results in deenergizing 1F and 2F (line 59), killing the voltage to the exciter GE (line 47). The deenergization of coil 2F (line 59) causes coil PFD (line 68) to be energized since the contact 2F2 has been opened. It is to be noted that coil PFF has already been deenergized. The opening of contact PFD5 (line 56) causes a setting of the brakes through relay coils BR1 and BR2 which are deenergized.

Trip from pit 4 to pit 2

Assuming the buggy at pit 4, the selector switch is set to close contact SS2. The push button Pit is closed and the circuit through contacts MR5, SS2, SLS22 and coil PRI to NEG is complete. With the energization of the coil PRI, the Pit button is shunted by the closed contact PRI3. At the same time of the closure of contact PR14 (line 69) leads to energization of coil PRV.

The energization of this coil causes coils RX, 2M and 2T (line 60) to be energized through closed contacts PRV1 and 1M3. Closure of contact PRI1 (line 61) completes the circuit from POS through contacts 2M3, 2F1 and relays 1R and 2R to NEG. The energization of coil 2R completes the holding circuit for the coil PRV (line 69) through closed contacts 2R3 and PRV5.

The energization of relays 2M and 2T (line 60) establishes the relation of generator 2G to boost voltage applied to motor 1M, causing it to "motor" and 2M to "drag." Energization of 1R and 2R establishes the direction of the GE Reference Field, hence the polarity of voltage 1G and the direction of movement of the ingot buggy (toward the mill).

The aforescribed energization of coil PRV (line 69)

closes the contact PRV6 (line 56) leading to the release of brakes through coils BR1 and BR2. The energization of coil RX (line 60) sets up the circuit from POS through the contacts RX1 (line 51), 1R3, the GE Reference Field, and the contact 1R2. The energization for this coil RX further establishes the circuit through the contact RX2 (line 52), 2G field, and contact RX3, determining the booster voltage polarity.

The energization of coil PRI (line 67) as aforescribed causes the coil IS (line 64) to be energized through the contacts PR12 and FS6. This causes closure of contact IS4 (line 51) completing the circuit for the GE Reference Field, causing the voltage to build up in generator 1G. This also in turn causes the coil ACC (line 62) to be energized through the closed contact IS2. The energization of ACC boosts the voltage of generator 2G, causing the motor 1M to "motor" and motor 2M tend to "drag."

As the buggy travels toward pit 2, the limit switch contact VLS2 is opened at spaced intervals but this has no effect since it is covered by the closed contact PRI1 (line 61). As the buggy comes close to pit number 2, limit switch contact SLS22 opens, thereby deenergizing the coil PRI (line 67). This would result in the opening of coil IS (line 64) because of the opening of contact PR12, however the circuit is covered through the closed contacts PRV3 and VLS4. When contact VLS4 is open on arrival near the pit 2, in due course, the coil IS is then deenergized.

The deenergization of coil IS opens contact IS4 (lines 51-52) and closes contact IS5, causing the voltage of generator 1G to decrease. The opening of contact IS2 and closure of contact IS3 causes the coil ACC (line 62) to be deenergized and coil DEC (line 63) to be energized, thereby modifying the "motor" action of motor 1M and the "drag" action of motor 2M. Deceleration is encouraged.

The final stop is effected when the limit contact VLS2 (lines 60-61) is open, the cover circuit through PRI1 now being open, thereby causing the coils 1R and 2R to be deenergized and killing the voltage of exciter GE. The deenergization of coil 2R causes the coil PRV (line 69) to be deenergized because of the openings of contact 2R3, the contact PRI4 being already opened. The opening of contact PRV6 (line 56) leads to the setting of the brakes through deenergization of coils BR1 and BR2.

Sequence of trip from pit 1 to pit 5

Assume the buggy is at pit 1. The selector switch SS is set to close the contact SS5. The Pit button (line 67) is pushed closed and the circuit from POS through MR5, SS5, SLS5, PFF4, and PFX1, and the coil PFI to NEG is completed. With the energization of coil PFI, the Pit button is shunted by the closed contact PFI4. Contact PFI5 (line 68) is also caused to close and this leads to the energization of coil PFD. This in turn energizes the coils FX, 1M and 1T, since the contacts PFD1 (line 58) and 2M2 are closed.

The aforescribed energization of coil PFI completes the circuit from POS through PFI1 (line 59) contacts 1M2 and 2R1 to energize the coils 1F and 2F. The energization of coil 2F completes the holding circuit for the coil PFD (line 68) through the closed contacts 2F2 and PFD4.

The energization of coils 1M and 1T establishes the direction of the GE Reference Field, hence the polarity of voltage 1G and the direction of movement of the ingot buggy from the mill (forward).

The energization of coil PFD (line 68) closes contact PFD5 (line 56) causing the brakes to be released through BR1 and BR2. The aforescribed energization of coil FX sets up the circuit from POS through contact FX1, 1F2, the GE Reference Field and 1F3.

The aforescribed energization of coil FX establishes

a circuit through FX3, 2G field and FX2, determining the booster voltage polarity.

The energization of coil PFI (line 67) energizes the coil IS (line 64) through the contacts PFI2 and FS4. This causes closure of contact IS4 (line 51) completing the circuit for the GE Reference Field, causing the voltage to build up in generator 1G. This also in turn energizes the coil ACC (line 62) through the contact IS2. The energization of coil ACC boosts the voltage of generator 2G causing the motor 2M to "motor" and motor 1M tend to "drag."

As the buggy travels toward pit 5, the limit switch contact VLS1 (lines 58-59) is open at spaced intervals, but this has no effect since it is covered by the closed contact PFI1 (line 59).

As the buggy comes close to pit 5, the limit switch contact SLS5 opens, thereby deenergizing the coil PFI (line 67). This would result in the deenergizing of the coil IS because of the opening of the contact PFI2 (line 64), however, the circuit is covered through the closed contacts PFD2 and VLS5. When the contact VLS5 is opened on approach of the ingot buggy to pit 5 in due course, the coil IS is deenergized. The deenergization of this coil opens the contact IS4 (line 51) and closes the contact IS5, causing the voltage of generator 1G to decrease. The opening of contact IS2 and closure of contact IS3 causes the coil ACC (line 62) to deenergize and the coil DEC (line 63) to energize, thereby modifying "motor" action of motor 1M. Deceleration is encouraged.

The final stop is effected when the limit contact VLS1 (lines 58-59) opens, the cover circuit through contact PFI1 (line 59) now being open, thereby the coils 1F and 2F (line 59) are deenergized, killing the voltage on the exciter GE.

The deenergization of coil 2F causes the coil PFD (line 68) to be deenergized since the contacts 2F2 and PFI5 are open. This in turn opens the contact PFD5 (line 56), leading to the setting of brakes through deenergized coils BR1 and BR2.

From the five aforescribed movements of the ingot buggy it should now be apparent to one skilled in the art that the operator can control various other movements of this buggy through the mill push button, the pit push button, and the selector switch.

It is to be understood that the aforescribed electrical circuit has been presented in a simplified form for the purposes of clarity and that various detailed modifications can be incorporated therein by one skilled in the electrical art.

I claim:

1. In combination with a row of spaced soaking pits and a metal rolling mill, an ingot buggy movable along said row to said rolling mill for transferring ingots, an ingot buggy drive system comprising a pair of spaced winches, said winches being positioned at opposite ends of said row of spaced soaking pits; a first cable having one end attached to one of said winches and its opposite end attached to one end of said ingot buggy; a second cable having one end attached to the other of said winches and its opposite end attached to the opposite end of said ingot buggy; a winch drive mechanism for each of said winches; a pair of motors, each motor being adapted to drive one of said winches through said winch drive mechanism; a pair of electrically controlled brakes, each being connected to one of said winch drives; a common generator system connected to both of said motors to supply electric power to both of said motors simultaneously and control means operatively connected to said generator system for selectively moving and positioning said ingot buggy, said control means including means for said generator system for governing delivery of greater voltages than a predetermined voltage by said generator system selectively to the armatures of said mo-

tors for causing differences in simultaneously opposed pulls on said cables connecting said winches with said ingot buggy so as to effect selected movement of said ingot buggy in its travel to and between said soaking pits and said metal working mill, said control means including further means to cause said brakes to effect a holding action when said motors are deenergized, and said control means also including cam actuated switch means for controlling movement of said buggy between pits and between the pits and said mill including a coarse cam actuated limit switch mechanism for controlling movement of the ingot buggy from pit to pit, and pit to mill; and a vernier cam actuated limit switch mechanism for accurate movement control of said ingot buggy between adjacent pits.

2. The apparatus of claim 1, wherein said control means includes means providing higher voltages to said motor armatures for selected extensive movements of said buggy than for selected less extensive movements of said buggy for thereby causing said buggy to travel at higher speed for the more extensive movements of the buggy

between the metal working mill and the pits most remote from the mill.
